UNITED STATES PATENT OFFICE.

WALTER LANE, OF HOLLAND, MICHIGAN, ASSIGNOR TO BUSH & LANE PIANO CO., OF HOLLAND, MICHIGAN.

UPRIGHT-PIANO FRAME.

1,146,432.

Specification of Letters Patent.

Patented July 13, 1915.

Continuation of application Serial No. 701,451, filed June 1, 1912. This application filed June 5, 1913.
Serial No. 771,827.

To all whom it may concern:

Be it known that I, WALTER LANE, a citizen of the United States, residing at Holland, Michigan, have invented certain new and useful Improvements in Upright-Piano Frames, of which the following is a specification.

This invention relates to improvements in upright piano frames, and this application is a continuation of my prior application, Serial No. 701,451, filed June 1, 1912, for frame bridge and sounding board for piano-fortes.

The objects of this invention are: first, to improve the tone of an upright piano by an improved arrangement and construction of the parts. Second, to add to the area of the sounding board in the treble by carrying the board up above the sounding board bridge and underneath the scale rib. Third, to improve the general structure and arrangement of the string plate and related parts.

Objects relating to details and economies of construction and operation will definitely appear from the detailed description to follow.

I accomplish the objects of my invention by the devices and means described in the following specification.

The invention is clearly defined and pointed out in the claims.

A structure constituting a preferred embodiment of my invention is illustrated in the accompanying drawing, forming a part of this specification, in which:

Figure I is a detail rear perspective view of a piano embodying the features of my invention. Fig. II is a front perspective view of the same, the entire front of the piano being removed and the strings being omitted. Fig. III is an enlarged detail, vertical sectional elevation through the treble end of the piano embodying the features of my invention taken on a line corresponding to line 3-3 of Fig. II, sufficient of the piano action being shown to make clear the relation of the parts. Fig. IV is an enlarged detail sectional view on the same line as Fig. III, through the scale rib 12, showing the position of the hammer in striking the string and its relation to the string and scale rib. Fig. V is an enlarged detail sectional view taken on a line corresponding to line

5-5 of Fig. I and showing in detail the construction of the joint between the frame 3 and the filler bar 3'.

In the drawing the sectional views are taken looking in the direction of the little arrows at the ends of the section lines, and similar numerals of reference refer to similar parts throughout the several views.

Considering the reference characters, the case, which is of the upright design, is formed of the base 1, the upright sides 2, 2, and the cross bar 4 connecting the upright sides at the top thereof. A continuous laminated frame 3 is provided which extends at the bass end substantially parallel to the side 2, and closely adjacent thereto, and which extends across the base for about two thirds of its length toward the treble end where it is then curved upwardly and laterally toward the treble end to a point from which it runs substantially parallel to but spaced from the side 2 to a point at about two thirds of the height of the case where said frame is curved toward the side 2 at the treble end of the case and extends parallel and adjacent to the side member 2 to the top of the frame. At the lower corner of the treble end of the frame there is provided a filler bar 3' of laminated construction which extends from the point where the frame 3 approaches the side member 2 at the treble end downwardly adjacent and parallel to said side member 2 to the bottom thereof and then transversely adjacent and parallel to the base 1 to the point where the frame 3 approaches said base member 1.

The filler bar 3', together with the frame 3 at the base end, makes a rim of substantially U-shape. A brace bar 5 is built into the laminated frame 3 at the bass end and extends from a point midway thereof upwardly and transversely for about one third of the distance across the back of the piano and then on a line substantially parallel with the top thereof to the treble side of the frame. An auxiliary brace bar 5' extends substantially in line with that portion of the brace bar 5 which is at the treble end of the piano from the frame 3 at the bass end of the piano to a point about one third of the distance across the piano where said auxiliary brace bar 5' joins the brace bar 5. The upper ends of this laminated frame 3 are connected by the cross bar 4 and by the up-

per part of string plate 6 and the wrest plank 7. The supporting brace bar 5 is beveled on its inner under side, as clearly shown in Fig. III, so as to provide a narrow support for the outer upper edge of the sounding board and thereby increase the resonance. The sounding board is securely glued to the frame at all points of contact therewith and is supported by said frame. 10 The center of the back of the piano is stiffened and supported by two or more laminated posts. A suitable joint is provided at the points where the ends of the filler bar 3' join the frame 3 and at the points 15 where the brace bar 5 joins the frame 3 and where the auxiliary brace bar 5' joins the brace bar 5. In Fig. V I have shown in detail the construction of a joint which may be made use of at these points although other suitable joints may very well be used.

The end of the filler bar 3' is first shaped so as to engage the periphery of the rim of the frame 3 perfectly. Glue is applied 20 to the contacting surfaces of the filler bar 3' and the frame 3, as indicated by the line 23 in Fig. V. This glue holds the parts together, but dowel pins may be used to assist in this. Holes are bored through the 25 rim 3 and the filler bar 3' and large maple dowels 24 are then inserted in these holes, as shown in Fig. V. The ends of these dowels are split and wedges 25 are fitted to the same. The wedges or dowels are thoroughly 30 glued and the wedges are driven into the split ends of the dowel pins, spreading the same. When the glue dries it is impossible 35 to remove the wedges and the frame, having been pressed together with a steel clamp, it is impossible to pull this joint apart. I have 40 shown this as a possible construction for the joints referred to above, but other constructions might very well be made use of.

The wrest plank 7, preferably of laminated wood, extends across the top of the frame and connects the upper ends of the laminated frame 3 together. The string plate 6 is secured thereto, having a rearwardly projecting flange 6' which extends 50 beneath the lower edge of the wrest plank and stiffens the plate at that point and affords support for the wrest plank. A forwardly projecting flange 6'' at the upper edge of the string plate adds greatly to the 55 rigidity of the structure.

The laminated wood which I use for all of these parts is made up of alternate layers of maple and walnut glued together, the layers being about half an inch thick for the posts 60 and about one eighth of an inch thick for the frame.

The treble end of the string plate is braced by the vertical braces 9, 10 and 11, which extend at 9', 10', and 11', to the lower 65 part of the plate 6. A scale rib 12 integral

with the braces and having a forwardly projecting rib 12' is disposed substantially parallel with and at some distance below the lower edge of the wrest plank, and said scale rib is supported in front of the sounding board and out of contact therewith by the extensions 9', 10' and 11' of the braces 9, 10, and 11, said braces forming the connection between the scale rib 12 and the string plate 6. A pressure bar 13, with a 70 rearwardly projecting rib, is disposed substantially parallel with the scale rib 12 and between the scale rib and the wrest plank and is carried by the extensions 9', 10', and 11' of the braces 9, 10, and 11. By this arrangement of the scale rib 12 and the pressure bar 13 and by allowing the sounding board to run above the scale rib and behind the same I have been able to gain in the area 75 of the sounding board in the extreme treble. This gives a greater amount of vibration, especially through the center and upper register. The scale rib 12 and the pressure bar 13 being supported by braces 9', 10' and 11', have a very solid bearing through the 80 treble registers. The strings 14 engage hitch pins 15 on the lower part of the string plate 6 and extend upwardly to the tuning pins 16, which extend through the string plate into the wrest plank 7. These are of 85 the usual construction and hence they will not be described in detail herein.

The sounding board 17 is secured to the laminated frame 3 and the bars 5 and 5' and extends over the entire back of the piano. 90 The sounding board has the usual ribs 18 which are beveled off at 19 toward each end, where they extend under the supporting frame and bars, the same extending into suitable mortises or gains therein. The 95 bridge 20, of the usual form, is supported on the sounding board 17 and is disposed in the usual position and in the usual relation to the strings, as shown in Fig. III.

The action 21 is of the usual or any desired construction provided with hammers 22, which are disposed to strike the strings 15 at a point 23' about one eighth of an 100 inch below the rib 12' of the scale rib 12, as clearly shown in Fig. IV.

By this arrangement of the supporting parts I have secured a construction at the treble end of my improved upright piano in which the sounding board extends three and five eighths inches above the treble 105 bridge, whereas, in the best makes of upright pianos to date, the sounding board usually extends about one and one quarter inches above the treble bridge. My construction gives a greater amount of vibration for the treble because the scale rib 12 is secured to the extensions 9', 10' and 11' of the braces 9, 10, and 11, which are integral 110 with the string plate 6. This gives a more solid support and a fuller tone. The 115

scale rib 12 not being connected with the wrest plank the tone is not absorbed by the wrest plank. The lower part of the string plate 6 is curved well out away from the 5 sounding board and in this manner I secure the fullest effect of the sounding board and secure very full and resonant tones. As shown in Figs. II and III, it will be noted that the plate 6 is curved away from the 10 sounding board 17 just below the point where the lower ends of the strings are attached.

The construction of the laminated frame 3 with the filler bar 3' and brace bars 5 and 15 5', which is shown and described in this application, is claimed in my co-pending application, Ser. No. 798,302, filed Oct. 30, 1913.

I am aware that my improved piano can 20 be considerably modified without departing from the spirit of my invention and I do not wish to be restricted to the structure here shown and described except as I am limited by my appended claims.

25 Having thus described my invention, what I claim as new and desire to secure by Letters Patent is:

1. An upright piano comprising the combination with the wrest plank and a suitably supported sounding board, with its upper edge clear of said wrest plank and in proximity thereto, of a full metal string plate provided with a flange projecting beneath the lower edge of the wrest plank, 30 and with an outwardly projecting flange at the top, a pressure bar with rearwardly projecting rib disposed parallel with and just below the lower edge of the wrest plank and supported separately therefrom, a scale rib 35 disposed just below the said pressure bar and parallel therewith and having a forwardly-projecting rib, upright brace bars integrally connected to the said string plate and carrying said scale rib and pressure bar and supporting the same in front of and out of contact with the sounding board, a suitable 40 bridge on the sounding board, strings disposed on said string plate, and a piano action with the hammers at the treble disposed to strike the strings at a point just beneath the scale rib, all coacting substantially as described and for the purpose specified.

50 2. An upright piano comprising the combination with the wrest plank and a suit-

ably supported sounding board, with its upper edge clear of said wrest plank and in proximity thereto, of a full metal string plate, a pressure bar disposed parallel with and just below the lower edge of the wrest plank and supported separately therefrom, a scale rib disposed just below the said pressure bar and parallel therewith and having a forwardly-projecting rib, upright brace bars 60 integrally connected to the said string plate and carrying said scale rib and pressure bar and supporting the same in front of and out of contact with the sounding board, all coacting substantially as described and for 65 the purpose specified.

3. An upright piano comprising the combination with the wrest plank and a suitably supported sounding board, with its upper edge clear of said wrest plank and in 75 proximity thereto, of a full metal string plate, a pressure bar disposed parallel with and just below the lower edge of the wrest plank and supported separately therefrom, a scale rib disposed just below the said pressure bar and parallel therewith, upright 80 brace bars integrally connected to the said string plate and carrying said scale rib and pressure bar and supporting the same in front of and out of contact with the sounding board, all coacting substantially as described and for the purpose specified.

4. An upright piano comprising the combination with the wrest plank and a suitably supported sounding board with its upper edge clear of said wrest plank and in proximity thereto, of a full metal string-plate disposed in front of said sounding board, strings fastened to said string plate at their lower ends and secured at their upper ends to pins passing through said string plate and into said wrest plank, said string plate being curved away from said sounding board at a point just below the point of attachment of the lower ends of said strings, 90 all coacting substantially as described and for the purpose specified.

In witness whereof, I have hereunto set my hand and seal in the presence of two witnesses.
